U.S. Appl. No. 29/281,695, Inventors Anzures et al., filed Jun. 28, 2007 (Not Published).

* cited by examiner

Primary Examiner — Melanie H Tung(74) *Attorney, Agent, or Firm* — Sterne, Kessler, Goldstein & Fox P.L.L.C.(57) **CLAIM**

The ornamental design for a display screen or a portion thereof with graphical user interface, as shown and described.

DESCRIPTION

The FIGURE is a front view of a display screen or portion thereof with graphical user interface showing our new design. The broken lines around the FIGURE showing a display screen or portion thereof form no part of the claimed design. The broken lines within the FIGURE show features that are not part of the claimed design.
